US00D427315S

United States Patent [19]**Saltzstein et al.****Patent Number: Des. 427,315****Date of Patent: ** Jun. 27, 2000**[54] **VITAL SIGNS MONITORING UNIT**

[75] Inventors: **William E. Saltzstein**, Woodinville, Wash.; **Mohamed Sabri**, Beaverton; **Scott M. Burkhardt**, Hillsboro, both of Oreg.; **Gregory T. Semler**, Menlo Park, Calif.

[73] Assignee: **Instromedix, Inc.**, Hillsboro, Oreg.

[**] Term: **14 Years**

[21] Appl. No.: **29/081,456**

[22] Filed: **Jan. 2, 1998**

[51] LOC (7) Cl. **24-01**

[52] U.S. Cl. **D24/186**

[58] Field of Search **D24/186; 600/345, 600/391, 393, 481, 484, 519, 513, 528, 532, 536, 538, 549, 586, 483, 485**

[57] **CLAIM**

The ornamental design for a vital signs monitoring unit, as shown and described.

DESCRIPTION

FIG. 1 is an isometric view of a vital signs monitoring unit in accordance with the present invention;
 FIG. 2 is a front view thereof;
 FIG. 3 is a rear view thereof;
 FIG. 4 is a right side thereof;
 FIG. 5 is a left side view thereof; and,
 FIG. 6 is a top view thereof.

UNITED STATES PATENT AND TRADEMARK OFFICE
CERTIFICATE OF CORRECTION

PATENT NO. : D427,315

DATED : June 27, 2000

INVENTOR(S): William E. Saltzstein, Mohamed Sabri, Scott M. Burkhart and Gregory T. Semler

It is certified that errors appear in the above-identified patent and that said Letters Patent is hereby corrected as shown below:

In the Description:

In Fig. 4, "right side thereof;" should read --right side view thereof;--.

Signed and Sealed this

Fifteenth Day of May, 2001

Attest:

NICHOLAS P. GODICI

Attesting Officer

Acting Director of the United States Patent and Trademark Office
